W. L. MERRILL

ELECTROMAGNETIC DEVICE

Filed Dec. 13, 1921

Inventor:
Wilbur L. Merrill,
by *Alfred S. Davis*
His Attorney.

UNITED STATES PATENT OFFICE.

WILBUR L. MERRILL, OF SCHENECTADY, NEW YORK, ASSIGNOR TO GENERAL ELECTRIC COMPANY, A CORPORATION OF NEW YORK.

ELECTROMAGNETIC DEVICE.

Application filed December 13, 1921. Serial No. 522,149.

My invention relates to improvements in electromagnetic devices, as for example electromagnetic switches, and has for its object the provision of means for preventing the vibration of the movable magnetic member of the electromagnetic device and the vibration of the switch member connected thereto in case the electromagnetic device is an electric switch.

10 My invention relates more specifically to improvements in electromagnetic devices for alternating current circuits. In certain types of electromagnetic switches, as, for instance, those in which the switch member is biased to an operative position by gravity or otherwise and is moved out of contact when a certain degree of energization of the winding is reached, some difficulty has been experienced due to the vibration of the contact. In switches of this character the winding is ordinarily energized constantly and the switch member moves up or down to either open or close the circuit depending upon the degree of energization of the winding. It has been found that under certain conditions as, for instance, where the frequency gets somewhat below that for which the switch was designed, there is a tendency for the contact to follow the line frequency and vibrate, thereby at times causing destructive arcing at the contacts. In other words, a switch, which at 60 cycles would have little or no tendency to vibrate, at 15 cycles might vibrate badly. This is because the core or magnetic movable member could not be accelerated in a sixtieth of a second whereas it might be accelerated in a fifteenth of a second and follow the line frequency. In carrying out my invention I give to the switch member or to the magnetic movable member connected to the switch member, or to the magnetic movable member and the switch member connected thereto, a certain amount of inertia without adding to the effective weight of the magnetic movable member and the switch member connected thereto which must be moved in response to the energization of the winding. This I accomplish in one form of my invention by applying to the magnetic movable member a weight which is balanced in some way as, for instance, by another weight so that the net weight of the parts to be acted upon by the winding is not increased.

50 Other objects and purposes of my invention

will appear in the course of the following specification in which I have shown my invention embodied in concrete form for purposes of illustration.

Referring to the drawing, it will be seen that I have illustrated the invention as embodied in an electromagnetic switch, and in this drawing 10 represents an energizing winding and 11 the core or magnetic movable member operated thereby. Attached to the lower end of the core is a contact disk 12 cooperating with stationary contacts 13. The winding 10, when energized to a certain value, will lift the contact disk 12 out of engagement with the contacts 13 and when the energization of the winding drops to a certain value the weight of the parts will carry the disk 12 into engagement with the contacts 13. This, of course, is a well-known form of switch and needs no further description.

If the winding 10 were energized by alternating current the moving parts of the switch would be designed so that they would not vibrate on say, for instance, a 60 cycle circuit. At this frequency the parts of a switch of this character could not be accelerated in the time necessary to set the parts vibrating with the frequency. If, however, the frequency should drop to a considerably lower value say, for instance, to 15 cycles such a vibration might readily be set up and cause arcing on the contacts 13, as well as an objectionable humming sound. In order to overcome these objections I have devised means whereby the inertia of the parts is increased so that even at a lower frequency the parts could not be accelerated. This I accomplish in the form shown in the drawing by means of two weights 14 and 15, which are arranged so as to counter-balance each other in their effect upon the core 11 and the switch parts.

The weight 14 is mounted upon one end of a rod 16, pivoted at 17, the opposite end of the rod being pivoted to the rod 18 upon which this contact 12 and the core 11 are mounted. Weight 15 is mounted at the middle portion of a rod 19 pivoted at one end at 20, and the opposite end of the rod being pivoted to the rod 18. The pivotal connections of these two arms 16 and 19 to rod 18 are slotted as shown and the weights 14 and 15 are adjustably mounted upon the rods. The weight 14 will obviously have a ten-

dency to force the switch parts upward whereas the weight 15 will have the opposite tendency; namely, to force the switch parts downward. Assume for the sake of 5 simplicity that the weight 15 weighs twice as much as weight 14; say, for instance, the weight 14 weighing 5 ounces and weight 15, 10 ounces, the leverage of weight 14 being 1:1, the weight 14 will exert an upward pull 10 on the switch parts equal to 5 ounces whereas the weight 15, being midway of rod 19, will exert a downward tendency equal to 5 ounces. The two weights, therefore, balance each other so far as concerns their effect 15 upon the weight of the core 11 and the other movable switch parts and the degree of energization of the operating winding 10 necessary to operate the magnetic member 11 is not altered. It is obvious however that 20 the inertia of the core and the switch contact 12 has been greatly increased and that with this increased inertia the core and the switch contact could not be accelerated even at a very low frequency. I have found that 25 by properly adjusting the weights and leverage a magnetic device of this character would be substantially free of vibration at the lowest frequencies which obtain in practice. It will be seen, therefore, that I have 30 provided means whereby the inertia of the parts is greatly increased without substantially affecting the weight which must be moved. In other words, there is substantially 35 no more pressure upon the contacts 13 than without the weights; in fact, there may be a little less due to the friction in the parts.

While I have described my invention as embodied in concrete form and as operating 40 in a specific manner in accordance with the provisions of the patent statutes, it should be understood that I do not limit my invention thereto, since various modifications 45 thereof will suggest themselves to those skilled in the art without departing from the spirit of my invention, the scope of which is set forth in the annexed claims.

What I claim as new and desire to secure by Letters Patent of the United States, is:—
50 1. An electromagnetic device for alternating current circuits, comprising a magnetizing winding, a magnetic movable member under the control of said winding, and means comprising a balanced movable mass 55 for increasing the inertia of the said member to prevent vibration due to the alternations of the magnetizing current of said winding without substantially increasing the degree of energization of the winding necessary to move the said magnetic member.

2. An electromagnetic device for alternating current circuits, comprising a magnetizing winding, a magnetic movable member under the control of said winding, and 60 means comprising a balanced movable mass

connected to the said member for imparting thereto a relatively high inertia to prevent vibration due to the alternations of the magnetizing current of said winding without substantially increasing the degree of 70 energization of the winding necessary to move the said magnetic member.

3. An electromagnetic device for alternating current circuits comprising a magnetizing winding, a magnetic movable member under the control of said winding, and an independently supported movable mass connected to said member for preventing vibration of the member due to the alternations of magnetizing current of said winding without substantially increasing the degree of energization of the winding necessary to move the said magnetic member. 75

4. An electromagnetic device for alternating current circuits comprising a magnetizing winding, a magnetic member operable between two positions responsively to a predetermined variation in the magnetizing current of said winding, and a balanced 80 movable mass pivotally supported independently of said magnetic member and connected thereto for preventing vibration thereof due to the alternations of the magnetizing current of said winding without substantially 85 changing the variation in the magnetizing current of the winding necessary to operate said magnetic member. 90

5. An electromagnetic device for alternating current circuits, comprising a magnetizing winding, a magnetic movable member under the control of said winding, and a plurality of pivotally mounted weights 100 connected to and balanced with respect to the said member for increasing the inertia 105 of said member to prevent vibration due to the alternations of the magnetizing current of said winding.

6. An electromagnetic switch for alternating current circuits, comprising a magnetizing winding, a magnetic movable member controlled thereby, a switch member normally in operative position which assumes either an operative or an inoperative position with varying degrees of energization 110 of the winding, the said switch member connected to the said magnetic member to be operated thereby, and means comprising a balanced movable mass for preventing the 115 said magnetic member and the said switch member from vibrating due to alternations of the magnetizing circuit. 120

7. An electromagnetic switch for alternating current circuits, comprising a magnetizing winding, a switch member normally 125 in operative position which assumes either an operative or inoperative position with varying degrees of energization of said winding, and means for increasing the inertia of the switch member to prevent vibration. 130

tion due to the alternations of the magnetizing circuit without substantially increasing the degree of energization necessary to move it.

5. 8. An electromagnetic switch for alternating current circuits, comprising a magnetizing winding, a switch member having a bias towards an operative position and movable into and out of said position upon varying degrees of energization of said winding, and means for increasing the inertia of said switch member without affecting the bias thereof.

9. An electromagnetic device for alternating current circuits, comprising a magnetizing winding, a magnetic movable member operated thereby to various positions depending upon the degree of energization of

said winding, a weight associated with said member to be accelerated upon movement of the member, and means for counterbalancing said weight whereby vibration of the member due to alternations in the magnetic circuit are prevented.

10. An electromagnetic switch for alternating current circuits comprising a magnetizing winding, a switch member operated thereby to various positions depending upon the degree of energization of said winding and balanced weights associated with said member for preventing vibration of the member due to alternations in the magnetizing circuit.

In witness whereof, I have hereunto set my hand this 12th day of December, 1921.

WILBUR L. MERRILL.
